(57) **CLAIM**

The ornamental design for a paper towel holder, as shown and described.

DESCRIPTION

FIG. 1 is a perspective view of a paper towel holder showing our new design.

FIG. 2 is a top view thereof.

FIG. 3 is a front view thereof.

FIG. 4 is a bottom view thereof.

FIG. 5 is a left side view thereof; and,

FIG. 6 is a right side view thereof.

The broken-line disclosure represents an unclaimed portion of the paper towel holder, and the short dash-long dash line represents an unclaimed boundary between an unclaimed surface and the surface forming part of the claimed design, that surface having been provided with surface shading.
